UNITED STATES PATENT OFFICE.

RUFUS MCKENNEY DILL, OF FREEPORT, MAINE.

LAMP-BURNER.

SPECIFICATION forming part of Letters Patent No. 310,392, dated January 6, 1885.

Application filed April 14, 1884. (No model.)

To all whom it may concern:

Be it known that I, RUFUS MCKENNEY DILL, of Freeport, in the county of Cumberland and State of Maine, have invented certain new and useful Improvements in Lamp-Burners; and I do hereby declare that the following is a full, clear, and exact description of the invention, which will enable others skilled in the art to which it appertains to make and use the same, reference being had to the accompanying drawings, and to letters of reference marked thereon, which form a part of this specification.

Figure 1 is a top plan. Fig. 2 is a bottom plan. Fig. 3 is a side elevation. Fig. 4 is a longitudinal section.

Same letters show like parts.

My invention relates to burners for lamps, and has more particular reference to those now known as "kerosene-oil" lamps. The great desideratum in burners of this description is, first, to obtain a sufficient and uniform supply of air to the flame in order to secure the requisite quantity of oxygen, and, second, to have the supply or current steady in order to keep the flame from flickering or wavering. If these objects are accomplished, the brightness and steadiness of the flame are promoted.

My invention also has relation to preventing the accumulation of oil on the top of the burner or around it, and also to prevent any unpleasant smell when the lamp is burning or after it has been extinguished.

a shows a cap with a slit, *b*, in the top thereof. This slit allows the wick-tube *c* to pass up through it, so that the lower edge of the cap *a* shall rest on the perforated plate *d*. This cap has perforations *e* in the top, and others, *f*, in the sides thereof, in the manner illustrated in the drawings. It will be seen, also, that when the cap *a* is placed in position on the perforated plate *d* a portion of the perforations are within the circumference of the cap and some of them outside of it. The object of the cap is to provide a uniform current of heated air from the chamber inside of the cap *a*, which current, uniting with that flowing toward the flame from the outside, furnishes an ample supply of oxygen to the flame, which burns with very great brilliancy and whiteness. The current coming up from the chamber formed by the cap

a through the perforations *e* and *f* insures steadiness to the air coming in contact with the flame. It prevents, in other words, the outside currents of air-supply from disturbing the steadiness of the flame. Both the outside and inside currents—*i. e.*, both those flowing toward the flame from within the cap and from outside of it—furnish a full supply of air. The combustion is thus rendered much more nearly perfect, and as a consequence a much larger flame can be employed—that is, the wick can be turned up higher than in other forms of burners—without smoking or the escape of the unconsumed resultants of imperfect combustion. The perforations in the plate *d*, that are outside the cap *a*, also furnish a supply of air to the flame; but the whole is steadied by the currents from the chamber formed by placing the cap *a* around the wick-tube, as has been described. In the bottom or plate *g*, I make a concavity, *h*. At the top or apex of this I construct a hole or holes, *i*. This is to conduct away from over the oil in the body of the lamp any gases that may form during the burning of the lamp by heat. By this means they are conducted to the flame of the lamp, being carried thither by the currents of air, and are consumed. At the base of the concavity or recess I construct other holes on a level with the top side of the plate or bottom *g*. These are openings to admit of the flowing back into the body of the lamp any oil that may accumulate on the plate or bottom *g*.

What I claim as my invention, and desire to secure by Letters Patent of the United States, is—

1. The cap *a*, resting on the perforated plate *d*, and having the slit *b*, the perforations *e* in the top, and the perforations *f* in the sides, in combination with and resting upon the perforated plate *d*, and in combination with the wick-tube *c*, as herein set forth.

2. The concavity *h*, with its perforations in the top and at a level with the plate or bottom *g*, as and for the purposes herein set forth.

In testimony that I claim the foregoing as my own I affix my signature in presence of two witnesses.

RUFUS MCKENNEY DILL.
